UNITED STATES PATENT OFFICE.

MATTHEW L. HOYT, OF LITTLEFALLS, NEW YORK, ASSIGNOR TO D. H. BURRELL & COMPANY, OF LITTLEFALLS, NEW YORK.

CENTRIFUGAL LIQUID-SEPARATOR.

SPECIFICATION forming part of Letters Patent No. 741,342, dated October 13, 1903.

Application filed March 25, 1903. Serial No. 149,528. (No model.)

To all whom it may concern:

Be it known that I, MATTHEW L. HOYT, a citizen of the United States, and a resident of Littlefalls, in the county of Herkimer and State of New York, have invented a new and useful Improvement in Centrifugal Liquid-Separators, of which the following is a specification.

This invention relates to the means for discharging the separated liquids—for instance, cream and skim-milk—from the rotating bowl in which the separation is effected, and has particular reference to that class of discharge devices which consist of an internal skimming-shield arranged within or underneath the cover of the bowl, as distinguished from discharge devices in which skim-milk-discharge pipes are used.

The objects of this invention are to produce a skimming-shield which is simple and compact, which causes a close separation of the cream and skim-milk, which is snugly arranged within the cover and forms a convenient support for the packing-ring which is applied to the joint between the body and cover of the bowl, and which has other advantages.

In the accompanying drawings, consisting of two sheets, Figure 1 is a vertical section of a bowl of a centrifugal creamer embodying this invention. Fig. 2 is a detached top plan view of the skimming-shield on an enlarged scale. Fig. 3 is a horizontal section through the neck of the skimming-shield on a level with the cream-screw in line 3 3, Fig. 5. Fig. 4 is a similar horizontal section on a level with the skim-milk-discharge openings in line 4 4, Fig. 5. Fig. 5 is a vertical section of the skimming-shield in line 5 5, Fig. 2, viewed in the direction of the arrow. Fig. 6 is a similar vertical section in line 6 6, Fig. 4. Fig. 7 is a fragmentary vertical section, on an enlarged scale, of the base of the skimming-shield and the adjacent parts of the bowl and cover. Fig. 8 is a detached side elevation of the skimming-shield. Fig. 9 is a fragmentary enlarged vertical section through one of the cream-discharge orifices in the top of the neck of the shield in line 9 9, Fig. 2. Fig. 10 is a fragmentary sectional elevation through the bowl and shield in line 10 10, Fig. 3.

Like letters of reference refer to like parts in the several figures.

A represents the body of the bowl of a creamer or other centrifugal liquid-separator, 55 which may be of any suitable form or construction.

B is the detachable top or cover of the bowl, which tapers upwardly to the usual cylindrical neck b. The cover is provided at its 60 base with a downwardly-projecting collar c, which is screw-threaded internally and is screwed upon the externally-threaded top d of the body of the bowl.

E represents the skimming-shield, which is 65 arranged within the cover and corresponds in its lower portion to the tapering or conical form of the cover. The base of the shield is provided with a circumferential flange e, having an external concave face or seat e', on 70 which is seated the rubber packing-ring f, which covers the inner side of the joint between the top of the body and the cover. The base of the shield rests upon an internal offset g, Fig. 7, near the top of the body, and 75 the base of the cover bears upon the base-flange of the shield and the packing-ring. The conical lower portion or body of the shield is arranged at a sufficient distance below the tapering main portion of the cover to form a 80 narrow but ample flow-space for the skim-milk between the cover and the shield. The skim-milk enters this flow-space through notches h, formed in the upper side of the base-flange e. The packing-ring extends 85 over these notches and the skim-milk passes upwardly through these notches below this packing-ring, as indicated in Fig. 7. The skimming-shield is provided with an upwardly-extending cylindrical neck H, which 90 fits snugly in the neck b of the cover and extends above the same, as shown in Fig. 1. At the base of the neck the shield is provided with an external shoulder h', which bears against the under side of the cover, adjacent 95 to the neck b thereof. The conical lower portion of the shield is provided on its outer side with several radial ribs i, four being shown, which extend from the shoulder h' downwardly to the base-flange e and are preferably of slightly-less depth than the space between the cover and shield, as shown in Fig. 10.

These ribs control the movement of the skim-milk in a circumferential direction and compel the skim-milk to reduce its speed as it flows from the zone of greatest radius and speed, at the base of the shield, upwardly and inwardly to the zone at the base of the neck, in which the radius and speed are much smaller. The shield is provided at the base of the neck with an inwardly-projecting annular flange K, which extends inwardly beyond the cream-zone and is provided with a radial notch k, Figs. 1 to 5, through which the cream flows upwardly into the neck of the shield. The outer portion of this cream-slot is obstructed by an adjusting-screw k', which extends to the outer side of the neck, so that it can be readily adjusted. The inner end of this screw controls the distance from the axis of rotation at which the cream is allowed to escape and the position of the cream-discharge with reference to the skim-milk discharge. This cream-notch is arranged between two upright ribs L, formed on the inner side of the neck of the shield and extending from the lower annular flange K to the annular top flange l of the neck. These flanges form an upright channel which confines the cream as it flows upwardly through the neck and directs the cream to the delivery-orifices l', formed between these ribs in the top flange l of the neck. The skim-milk passes from the flow-space on the outer side of the lower portion of the shield into the neck at the lower end of the latter by openings m, which are formed in the neck of the shield outside of the cream-confining ribs L. The skim-milk flows upwardly through the neck until it reaches the delivery-openings n, which are formed in the neck of the shield above the neck b of the cover. The construction of the shield and its passages by which the skim-milk and cream or other separated liquids are both caused to flow into the neck of the shield and discharged from the inner side thereof places the discharge-levels of the two separated liquids very closely together. This is not the case in other devices of this general character in which the cream or light liquid passes into the neck of the shield and the skim-milk or heavy liquid remains on the outer side of the neck, because in the last-mentioned structures the thickness of the metal of the neck always lies between the discharge-levels of the two separated liquids. The improved construction herein described therefore admits of a very close relative location and adjustment of the cream and skim-milk discharges, whereby the efficiency of the machine in skimming the milk is considerably increased. The shield removes the skim-milk from the bowl at numerous points circumferentially around the top of the body of the bowl, whereby cross-currents in the liquid are prevented, and it effectually controls the speed of the skim-milk as the latter passes from the zone of the greatest radius and speed to zones of lower radii and speeds. The shield can be

readily removed from the cover for cleaning, and all of its parts and passages are readily accessible for that purpose. The shield also forms a convenient and firm support for the packing-ring, and the arrangement of the latter on the base of the shield permits the top of the bowl to be made comparatively narrow and light, whereby the construction of the bowl is simplified and the cost of manufacture is reduced.

I claim as my invention—

1. The combination of a centrifugal liquid-separator bowl and a skimming-shield arranged within the bowl, said shield having passages for the delivery of the light and heavy separated liquids from the interior of the shield, a passage through which the heavy separated liquid passes from the exterior of the shield to the interior thereof, and means for keeping the separated liquids separate within the shield.

2. The combination of a centrifugal liquid-separator bowl having a contracted neck and a skimming-shield within the bowl, having a neck arranged within the neck of the bowl, said shield having passages for the delivery of the light and heavy separated liquids from the interior of the neck of the shield, a passage through which the heavy separated liquid passes from the exterior of the shield to the interior of the neck thereof, and means for keeping the separated liquids separate in the neck of the shield.

3. The combination of a centrifugal liquid-separator bowl having a contracted neck and a skimming-shield within the bowl, having a neck arranged within the neck of the bowl, said shield having a passage for the upward flow of the light liquid in the lower portion of the neck, internal upright ribs above said passage and on opposite sides thereof, a delivery-passage for the light liquid between said ribs in the upper portion of the neck, and a passage for the heavy liquid leading from the exterior of the shield into the neck thereof outside of said ribs.

4. The combination of a centrifugal liquid-separator bowl having a contracted neck and a skimming-shield within the bowl, having a neck arranged within the neck of the bowl, said shield having in its neck an annular base-flange provided with a cream-discharge passage, a cream-delivery passage above said discharge-passage, upright ribs on opposite sides of said passages, and a skim-milk passage leading from the exterior of the shield to the interior of its neck outside of said ribs.

5. The combination of a centrifugal liquid-separator bowl having a contracted neck and a skimming-shield within the bowl, having a neck arranged within the neck of the bowl, said shield having on the inner side of its neck a cream-channel extending upwardly, a flow-space for the skim-milk outside of said channel, and a passage through which the skim-milk enters said internal flow-space from the exterior of the shield.

6. The combination of a centrifugal liquid-separator bowl having a contracted neck and a skimming-shield within the bowl, having a neck arranged within the neck of the bowl, 5 said shield having its lower portion separated from the top of the bowl by a flow-space for the skim-milk and having a passage leading from said flow-space to a flow-space on the interior of the neck, an internal upright cream-channel, and delivery-orifices for the cream from said channel and for the skim-milk from the internal flow-space outside of said channel.

7. The combination of the body of a centrifugal liquid-separator bowl, a detachable cover, a tapering skimming-shield arranged within the cover with its base adjacent to the joint between said body and cover, and having passages for the delivery of the light and 15 heavy separated liquids from its small end, 20 and a packing which bears at its inner side

against the shield and at its outer side against the bowl and the cover.

8. The combination of the body of a centrifugal liquid-separator bowl, a detachable 25 cover, a tapering skimming-shield arranged within the cover and having passages for the delivery of the light and heavy separated liquids from its small end, said shield being provided at its base with a marginal flange 30 having notches for the passage of the heavy separated liquid, and a packing-ring which is arranged on said flange and extends circumferentially over said notches and bears at its outer side against the joint between 35 the body of the bowl and the cover.

Witness my hand this 23d day of March, 1903.
